VENTED MOLD AND APPARATUS FOR
MAKING SAME

William H. Millspaugh, Catawba Island, Ohio,
assignor to Centrifugal Steel, Inc., Sandusky,
Ohio, a corporation of Ohio

Application May 23, 1935, Serial No. 22,935

11 Claims. (Cl. 22—16)

This invention relates to vented molds and to the method of making same.

Its object is to improve upon molds previously used and to provide a novel method of making them.

Refractory lined molds are used in making certain types of castings centrifugally. Such gases as are entrapped between the casting and the inner surface of the mold or which are liberated in the mold lining itself, must escape outwardly in order to make a perfect casting. To that end it has been necessary heretofore to provide perforated flasks. In making certain castings cooling water is applied to the outside of the flask. When the latter is perforated this dampens the refractory liner and causes vapor pressure to be developed which results in injury to the casting. This difficulty may be overcome by making a vented mold within a solid flask in the manner herein set forth.

I will describe two methods of making vented molds according to my invention.

Referring to the drawing,

Fig. 1 is a sectional elevation of a vented mold in process of construction and of the parts which are used for making it;

Fig. 2 is a perspective view of a plug or pattern and vent forming equipment which is shown in Fig. 1;

Fig. 3 is a partial enlarged sectional elevation of some of the parts shown in Fig. 1;

Fig. 4 is an inverted sectional plan view of the parts shown in Fig. 3, the section being taken on the line 4—4 of Fig. 3;

Fig. 5 is a view similar to Fig. 3 illustrating another construction;

Fig. 6 is a plan view of the parts shown in Fig. 5, the section being taken on line 6—6 of Fig. 5; and

Fig. 7 is a sectional elevation of a part of the upper portion of a finished mold made according to this invention and a face plate affixed to a rotor, a part of which is shown.

Like characters of reference designate corresponding parts on each side of the figures.

10 designates a hollow cylindrical flask of indeterminate length and with imperforate walls. In forming a refractory liner within this flask, a stop-off 11 is placed within it in a position which predetermines the length of the finished mold and the flask is placed in a vertical position.

The stop-off is constructed with a central part forming a cylindrical opening 12, and a flat disc 13 placed slightly below the upper edge of this

central part to form an annular shoulder 14. Its outer portion 15 is cylindrical and is adapted to fit the inner surface of the flask 10. This is provided with a plurality of grooves 16, parallel with its axis and extends up above the disc 13 to form a shoulder 17. 18 is a facing on the disc 13 between the shoulders 14 and 17 and preferably overlapping the former. This facing may be a metal plate or of refractory material as shown, either rammed and dried in place or pre-molded. Its object is to protect the stop-off in use from injury from excessive heating. 19 is an annular band of a fusible plastic material such as wax, tar, bituminous matter or a mixture of suitable materials, in the upper, outer part of the shoulder 17 which is recessed to receive it, as best shown in Fig. 3.

20 is a cylindrical ramming plug, the outer diameter of which is that of the inner diameter of the finished mold. This is suspended by ropes or cables 21, by means of which it may be lowered onto the stop-off 11. 22 is a boss which projects below the plug 20 into the opening 12 of the stop-off to center the lower end of the plug.

23 are guides affixed to the upper end of the plug 20 which extend outwardly to fit the flask 10 to center the upper end of the plug. 24 is a ring which rests upon or is affixed to the guides 23. Affixed to the ring 24 and depending therefrom is a plurality of rods 25. These are substantially half round in cross-section with their flat or nearly flat sides lying against the inner surface of the flask. Their lower ends extend below the lower end of the plug 20. This forms what has been referred to as a vent forming equipment.

When the plug is lowered onto the stop-off, the rods 25 penetrate the plastic ring 19 and will be held thereby against displacement during the first part of the ramming operation which I will now describe.

With the parts in the relative positions in which they are shown in Fig. 1, refractory material 30 is dropped into the space between the inside of the flask 10 and the outside of the plug 20, a part of which space is occupied by the rods 25. As this material is supplied it is rammed or tamped down into a nearly solid mass. This operation is continued so that a liner is built up gradually around the plug 20 with the rods 25 embedded in it.

After the liner has been thus formed around the plug, for at least a substantial part of its length, the plug is raised in the liner but not out of it. Its lower end is then centered in the liner itself.

The rods 25 are raised with the plug leaving voids 26 in the liner in the places originally occupied by the rods.

More refractory material is then supplied and tamped until the lining is built up far enough to guide the lower end of the plug when it is raised to a still higher position. These steps are continued until the ring 24 is raised above the top of the flask. Refractory material is still supplied and tamped in place until the liner is completed to the end of the flask. Then the plug and the rods are hoisted clear of the lined flask, a stripping plate being provided to hold the top of the mold from lifting.

The lined flask is thereafter put in a drying oven and subjected to heat, applied for the primary purpose of baking the refractory material. The heat, however, has the further effect of melting the plastic ring 19, and it will run out leaving an annular void in the space it originally occupied.

Thus, a mold comprising an imperforate flask with a refractory lining is produced with longitudinal vent channels extending from end to end.

The stop-off 40, shown in Figs. 5 and 6, differs from that previously described in that the upper portion of its outer part is provided with grooves 41 shaped to receive the ends of rods 25. These grooves extend down to and communicate with an annular cavity 42. Vent grooves 43 are shown extending from this cavity 42 to the bottom of the stop-off, but with this construction these are not necessary. Axial passages 44 extend inwardly from the annular cavity to the bottom of the stop-off.

The method of constructing a mold with this form of stop-off is similar to that already described, except that there is no plastic ring to be melted out. The passages 44 are extended inwardly so that any foreign matter which may be dislodged during the operation of the mold, which might fall into the annular cavity 42, will be retained therein by centrifugal force and will not pass into the passages 44 to clog them or to be discharged through them.

In Fig. 7, a face plate which is affixed to the end of a rotor 51, holds the finished mold in place. The upper end of the flask is flanged and held between the face plate and the rotor. A packing or seal 52 is placed between the upper end of the liner 30 and a facing similar to that in the stop-off (Fig. 3). An annular space 53 is formed around the outside of the seal. Radial grooves 54 in the inner surface of the face plate communicate with this annular space and provide for the escape of air or gases from the voids 26.

For illustrative purposes, I have shown two forms of molds which embody this invention and two ways of making them, but other forms and other methods may be made and used within its spirit and scope and I intend no limitations other than those imposed by the appended claims.

What I claim is:

1. A mold comprising an imperforate flask, a liner of refractory material therein constructed to form a plurality of parallel longitudinal venting passages therein extending through the ends of said liner, and a transverse stop-off constructed to form passages communicating with the passages in the liner.

2. A mold comprising an imperforate flask, a liner of refractory material therein constructed to form a plurality of parallel longitudinal venting passages therein adjacent the inner surface 75 of the flask, extending through the ends of said

liner, and a transverse stop-off constructed to form passages communicating with the passages in the liner and leading inwardly therefrom.

3. A mold comprising an imperforate flask, a liner of refractory material therein constructed to form a plurality of parallel longitudinal venting passages therein adjacent the inner surface of the flask, extending through the ends of said liner, and a transverse stop-off constructed to form an annular cavity communicating with the passages in the liner and a passage leading inwardly from said cavity and out through the end of the stop-off.

4. A mold comprising an imperforate flask, a liner of refractory material therein constructed to form a plurality of parallel longitudinal venting passages therein adjacent the inner surface of the flask, extending through the ends of said liner, and a transverse stop-off constructed to form an annular cavity communicating with the 10 passages in the liner and a plurality of radial passages leading inwardly from said cavity and out through the end of the stop-off.

5. A device for lining cylindrical flasks comprising a longitudinally movable plug of less diameter than the inner diameter of the flask, an annular ring arranged to fit slidably within the flask carried by one end of the plug and movable therewith to center and guide the plug, and a plurality of rods parallel with the axis of the plug 30 affixed to said ring.

6. A cylindrical flask and a stop-off therein combined with a longitudinally movable plug of less diameter than the inner diameter of the flask, means for centering one end of the plug 35 in the stop-off, an annular ring arranged to fit within the flask carried by the other end of the plug and to center said end and movable with the plug, a plurality of rods parallel with the axis of the plug affixed to said ring, and means for 40 positioning the ends of the rods in said stop-off.

7. A cylindrical flask and a stop-off therein combined with a longitudinally movable plug of less diameter than the inner diameter of the flask, arranged to be seated on the stop-off and to be centered thereby, an annular ring arranged to fit within the flask carried by the other end of the plug and to center said end and movable with the plug, a plurality of rods parallel with the axis of the plug affixed to said ring and extending beyond the other end of the plug into 50 the stop-off when the plug is seated thereon.

8. A cylindrical flask, a stop-off therein and an annular ring of fusible plastic material seated in the stop-off combined with a longitudinally movable plug of less diameter than the inner diameter of the flask, arranged to be seated on the stop-off and to be centered thereby, an annular ring arranged to fit within the flask carried by the other end of the plug and to center said end and movable with the plug, and a plurality of rods parallel with the axis of the plug affixed to said ring, extending into said annular ring when the plug is seated in the stop-off.

9. A cylindrical flask and a stop-off therein combined with a longitudinally movable plug of less diameter than the inner diameter of the flask, arranged to be seated on the stop-off and to be centered thereby, an annular ring arranged to fit within the flask carried by the other end of the plug and to center said end and movable with the plug, a plurality of rods parallel with the axis of the plug affixed to said ring, extending beyond the other end of the plug into the 70 75 95

stop-off when the plug is seated thereon, and means for moving the plug and the rods longitudinally.

- 5 10. A cylindrical flask, a stop-off therein combined with a longitudinally movable plug of less diameter than the inner diameter of the flask, arranged to be seated on the stop-off and to be centered thereby, an annular ring arranged to fit within the flask carried by the other end of the plug and to center said end and movable with the plug, an annular ring of fusible plastic material seated in the stop-off, a plurality of rods parallel with the axis of the plug affixed to said ring carried by the plug, extending into said ring of

plastic material when the plug is seated in the stop-off, and means for moving the plug and the rods longitudinally.

11. A mold comprising an imperforate flask, a liner of refractory material therein constructed to form a plurality of parallel longitudinal venting passages therein extending through the ends of said liner, a transverse stop-off at one end of the liner, and a face plate at the other end of the liner, said stop-off and face plate being constructed to form passages communicating with the passages in the liner. 5 10
